UNITED STATES PATENT OFFICE.

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed June 4, 1925, Serial No. 34,876. Renewed June 21, 1928.

This invention relates to the manufacture of shoes and is disclosed herein as embodied in a fastening-inserting machine having means for locating an insole in predetermined relation to a last while a fastening is driven through the insole into the last.

The requirements of good shoemaking necessitate that each insole be secured to its last with a very considerable degree of accuracy, both longitudinally and transversely. It has been proposed, moreover, as set forth in Letters Patent of the United States No. 1,674,060, granted June 19, 1928, on my co-pending application, Serial No. 8,717, filed February 12, 1925, to utilize alining holes through the insole and in the last to position the insole and last relatively to the operating instrumentalities of a lasting machine. This requires that the insole be secured to the last with said holes in substantially mathematically exact alinement so that a pin or pins carried by part of the lasting machine may be introduced into these alining holes.

It is, accordingly, an object of the present invention to provide a fastening-inserting machine organization having positioning surfaces arranged to co-operate with corresponding positioning surfaces formed upon an insole and a last to position the insole in a predetermined relation to the last while a fastening is inserted through the insole into the last. These positioning surfaces advantageously may take the form of one or more pins carried by a work-engaging element of the machine and co-operating with corresponding holes formed through the insole and in the last. In order to insure the proper angular relation of the insole to the last and positively to prevent relative movement of the last and the insole in all directions transversely of the insole, the illustrated machine is provided with two of these positioning pins and the insoles and lasts are provided with corresponding pairs of holes, the positioning pins being located near the nozzle of the machine so that the first fastening inserted through the toe portion of each insole into the last will be driven just forwardly of the positioning pins.

It is the usual practice to attach an insole to a last by a plurality of fastenings driven through different parts of the insole into the last. In order to facilitate this, a feature of

the invention comprises means for withdrawing the positioning surfaces of the machine from the corresponding positioning surfaces of the insole and last so that the work may be moved relatively to the fastening, inserting instrumentalities of the machine when a sufficient number of fastenings has been inserted to prevent inadvertent displacement of the insole relatively to the last, thus permitting the ready presentation of different portions of the insole for the insertion of additional fastenings. Thus the illustrated machine is provided with means arranged automatically to move the positioning surface carrying member away from the work immediately after the insertion of the first fastening and to latch it in inoperative position while subsequent fastenings are inserted.

After the insertion of all the fastenings necessary in one piece of work, it is desirable that the positioning surfaces should be returned to operative position before the next work piece is presented. Accordingly, another feature of the invention comprises means, herein disclosed as manually controlled, for releasing the positioning surface carrying member after the insertion of the fastenings in a given work piece to permit the return of the positioning surfaces to operative position. As illustrated, this releasing means includes a member located adjacent to the position occupied by the forward extremity of the last at the conclusion of the insertion of fastenings so that the operator may conveniently strike the last against said member and by impact of the last trip the latch which holds the positioning surface carrying member in inoperative position so that the latter will move into position for engagement with the next insole and last.

In order that the different fastenings inserted into each last at different times during the manufacture of different shoes thereon may not all be driven into the same hole, which would thus become enlarged and fail to hold the fastenings, a further feature of the invention comprises the mounting of the positioning surface carrying member of the machine in such a manner that it may be moved or adjusted relatively to the fastening-inserting instrumentalities of the machine without in any way changing the position at which an insole is located relatively to a last.

With the above and other objects and features in view, the invention will now be described with reference to the accompanying drawings and pointed out in the claims.

5 In the drawings,

Fig. 1 is a side elevation of the head of a fastening-inserting machine, with certain parts shown in cross-section;

Fig. 2 is a front elevation, on a larger scale than Fig. 1, of the work-positioning member of Fig. 1 and its latching and releasing mechanism;

Figs. 3 and 4 are side elevations on a larger scale than Fig. 1 and also partly in section, Fig. 3 showing the work-locating means in operative position and Fig. 4 showing it withdrawn from the work and in inoperative position.

The present invention is illustrated herein as embodied in a machine of the type illustrated in United States Letters Patent No. 1,106,393, granted August 11, 1914, on an application filed in the name of Fred L. MacKenzie, to which reference may be had for a fuller description of the machine. In brief, the machine includes a nozzle 10 through which reciprocates a driver 12 carried by a driver bar 14. Driver bar 14 is reciprocated once during each cycle of operation of the machine, moving downwardly to cause the driver to drive a tack through the nozzle into the work and then returning to its elevated position where it is held when the machine comes to rest. The specific mechanism for accomplishing this, as well as the controlling means for the machine as a whole, are not described herein since they are well known in the art and may take various forms so far as the present invention is concerned.

40 Mounted for reciprocating movement in a slideway carried by the head of the machine and parallel to the driver bar 14 is a second reciprocable bar 16, to the lower end of which is adjustably secured a positioning surface 45 carrying member 18. At the lower end of member 18 and located adjacent to the nozzle 10 of the machine are provided positioning surfaces, illustrated in the form of two pins 20 arranged to engage with corresponding 50 positioning surfaces illustrated as holes 22 formed through the insole 24 and corresponding holes 26 formed in the last 28 to which the insole is to be tacked, arranged positively to hold the last and the insole against relative movement in all directions transversely of the insole. When bar 16 is in its lowermost position, as illustrated in Fig. 3, pins 20 are in position to be received in holes 22 and 26 of the insole and last, locating the insole and last, as shown in Fig. 3, for the insertion of a tack toward the toe of the last. Since the holes through the insole and in the last are only big enough to provide a good working fit for pins 20, the insole and the last must 60 be properly positioned relatively to each

other before the first fastening is inserted. After the first fastening has been inserted it is desired to move the insole and last forwardly, that is to the left as illustrated in Fig. 1, so that additional fastenings may be 70 inserted, for example at the ball line and toward the heel. To facilitate this, the illustrated machine is arranged so that the positioning surface carrying member 18 is automatically moved to inoperative position, as 75 shown in Fig. 4, after the first fastening has been driven and secured in that position by a latch 30 carried by a rock shaft 32 having a bearing in a stationary part of the head of the machine, latch 30 being urged in a counter-clockwise direction, as shown in Figs. 1, 3 and 4, by a spring 34 housed in a socket 36 formed at the lower end of the latch. A notch 38 formed in bar 16 serves for engagement with latch 30, holding bar 16 in elevated position against the resistance of a compression spring 40 housed in bar 16 and bearing at its upper end against a surface 42 formed on the head of the machine. Driver bar 14 carries a pivoted dog 44 (Figs. 3 and 4) having at 85 its upper end a finger 46 normally urged toward bar 16 by a leaf spring 50 engaging the lower end of dog 44 and tending to rock it in a clockwise direction, as viewed in Fig. 3. A shoulder 48 is formed upon bar 16, so located that when bar 16 is in its lower, or operative, position, finger 46 of dog 44 will snap under shoulder 48 (Fig. 3) as the driver bar 14 reaches its lowermost position in the first cycle of operation when the machine is 95 started. Then, as driver bar 14 moves upwardly on its return stroke it lifts bar 16 against the compression of spring 40, as shown in Fig. 4. At its lower end dog 44 is provided with a lug 52 arranged for engagement, as 100 the driver bar is elevated, with a cam surface 54 formed upon a hard plate 56 carried by the head of the machine so as to rock dog 44 in a counter-clockwise direction when driver bar 14 has moved upward a short distance. 105 By this time, however, bar 16 will have been latched in elevated position by latch 30 which, as has been already pointed out, is urged by spring 34 toward bar 16. Thus positioning pins 20 will be elevated automatically as 110 driver bar 14 makes its return stroke after driving the first fastening and will be secured in elevated position. Accordingly, the insole and last may be moved longitudinally and other fastenings driven without interference by positioning pins 20, the operator, of course, grasping the insole and last so as to prevent inadvertent movement of the insole relatively to the last between the driving of the first and the second fastenings. Bar 16, 115 member 18 and pins 20 remain latched in elevated position while successive fastenings are driven into the insole and last. When sufficient fastenings have been driven, it is desirable to return bar 16 and positioning pins 120 125 130

20 to operative position. Accordingly, manually-controlled means is provided for releasing latch 30, and in order to facilitate this, these releasing means include a plate 60 (Figs. 5 1 and 2) located adjacent to the position occupied by the toe of the last when the last fastening is inserted. Plate 60 is carried by a bell crank lever 62 arranged to be rocked by impact of the work and connected by a link 10 64 with a lever 66 rigidly secured to rock shaft 32 so that when the operator strikes the toe of the last against plate 60, latch 30 will be rocked in a clockwise direction, as viewed in Figs. 1, 3 and 4, thereby releasing bar 16 15 so that it may move downwardly under the influence of spring 40 to bring pins 20 into work-engaging position ready for the operation upon the next work piece.

In order to prevent the different fastenings 20 driven into each last during the manufacture of different shoes thereon from all being driven in at the same point and thereby soon putting the last in such a condition that the fastenings will not hold, means is provided 25 for adjusting or moving the positioning pins 20 relatively to the nozzle 10. As illustrated this is done by connecting member 18, which carries pins 20, to bar 16 by a universal joint or pivot. As herein shown, a ball 70 is 30 formed upon the lower end of bar 16, the ball 70 being received in a socket formed in two parts of member 18, these two parts being clamped together, and to ball 70 by a bolt 72. Then if the position of member 18 35 relatively to bar 16 is changed occasionally, for example once a week or once in several weeks, the position at which the tacks will be inserted relatively to the positioning pins 20 will be varied from time to time. Or, if desired, 40 the connection between member 18 and bar 16 may be left a little loose with the same result. The position of the insole relatively to the last will be the same under all circumstances irrespective of the distance between 45 positioning pins 20 and the nozzle so that the accuracy of the work will be in no way affected by the changes in the position of member 18.

Having described the invention, what I 50 claim as new and desire to secure by Letters Patent of the United States is:

1. A fastening-inserting machine having, in combination, means for positioning an insole relatively to a last comprising a member provided with one or more pins arranged 55 to enter corresponding holes formed in the insole and last to position the insole relatively to the last, and means for driving a fastening through the insole thus positioned into the 60 last.

2. A shoe machine having a work-controlling member provided with one or more pins arranged to be passed through one or more holes formed in one article into a correspond- 65 ing hole or holes formed in another article

to position said articles in predetermined relation to each other, means operating through a succession of cycles for performing an operation upon the articles while thus positioned, and means for withdrawing 70 said pin or pins substantially at the conclusion of the first cycle of operation of said means.

3. A fastening-inserting machine having work-controlling means comprising a member provided with one or more pins arranged to be inserted through one or more holes formed in an insole into a corresponding hole or holes in a last to position the insole in predetermined relation to the last, a driver, 75 means for operating the driver to insert a fastening through the insole thus positioned into the last, and means for withdrawing the pin or pins from the insole and last after the insertion of a fastening.

4. A fastening-inserting machine having work-controlling means comprising a member provided with a plurality of pins arranged to be inserted through holes formed in an insole into corresponding holes in a last to position the insole in predetermined relation to the last, a driver, means for operating the driver to insert a plurality of fastenings through the insole thus positioned into the last, and means for withdrawing the pins from the insole and last after the insertion 90 of the first of said fastenings.

5. A fastening-inserting machine having, in combination, a work-positioning member, a positioning pin carried by said member arranged to co-operate with a corresponding hole formed in an insole and a last positively to position the insole in predetermined relation to the last, a driver, and means for reciprocating the driver to insert a fastening through the insole into the last while the insole and last are thus positioned.

6. A fastening-inserting machine having work-positioning means arranged to hold two parts in predetermined position against relative movement in all directions transversely thereof during the insertion of a fastening therein, and power operated means for withdrawing the work-positioning means after the insertion of said fastening.

7. A fastening-inserting machine having cyclically operating means for inserting in succession a plurality of fastenings, work-positioning means arranged to hold two parts positively in predetermined position during 120 the insertion of the first fastening therein, and means for automatically withdrawing the work-positioning means after the insertion of said first fastening.

8. A fastening-inserting machine having, in combination, a reciprocable bar, a plurality of pins carried by said bar arranged to be inserted in holes formed in an insole and last to position the insole in predetermined relation to the last, a driver, mechanism for 125

operating the driver to insert a fastening through the insole into the last to secure the insole to the last, and mechanism operated by the driver operating mechanism to move 5 said bar in a direction to withdraw said pins from the last and insole and to latch said bar in withdrawn position after the insertion of the fastening.

9. A shoe machine, having cyclically 10 operated instrumentalities for operating upon a shoe part, a work-positioning member, means operative approximately at the conclusion of the first cycle of operation to move said work-positioning means to an 15 inoperative position and to latch it in said inoperative position, and manually operable means for releasing said latching means to permit the return of the work-positioning means to operative position.

10. A fastening-inserting machine having fastening-inserting means, a work-positioning member, means operative after the insertion of a fastening to move said work-positioning means to an inoperative position and 25 to latch it in said inoperative position, and manually operable means for unlatching the work-positioning means to permit its return to operative position.

11. A fastening-inserting machine having, 30 in combination, a work-positioning member provided with one or more pins arranged to enter corresponding holes formed in an insole and a last to position the insole in predetermined relation to the last, a driver, means 35 for reciprocating the driver to insert a fastening through the insole into the last while the insole and last are thus positioned, and means for withdrawing the pin or pins immediately after the insertion of said fastening.

12. A fastening inserting machine having, 40 in combination, a reciprocable bar, a work-positioning member carried by said bar and provided with positioning surfaces arranged 45 to co-operate with corresponding positioning surfaces formed upon an insole and a last to position the insole in predetermined relation to the last, means for driving fastenings through the insole into the last to secure the 50 insole to the last, mechanism operated by said means to move said bar away from the insole after the insertion of the first fastening, thereby withdrawing said pins from the last and insole, and a latch arranged to hold said bar 55 in withdrawn position.

13. A fastening-inserting machine comprising a reciprocable driver bar, another reciprocable bar adjacent thereto and provided 60 with work-positioning surfaces, a dog carried by the driver bar and arranged during the retraction of the driver bar to move the other bar from operative to inoperative position, and a latch arranged to hold said last-named bar in inoperative position.

65 14. A fastening-inserting machine having

fastening-inserting means, work-positioning means arranged to hold two parts in predetermined position during the insertion of a fastening therein, means for withdrawing the work-positioning means after the insertion of 70 a fastening, a latch for holding the work-positioning means in withdrawn position arranged to permit further operation of the machine with the work-positioning means in inoperative position, and means for releasing 75 the latch to permit the return of the work-positioning means to operative position, said latch releasing means including a member positioned near the normal position of a portion of the work at the conclusion of the insertion of the fastenings and operable by impact of the work to release said latch.

15. A shoe machine having, in combination, a reciprocable bar provided with work-positioning surfaces, a dog arranged after the 80 performance of an operation on the work to move said bar to inoperative position, and a latch arranged to hold said bar in inoperative position and to permit further operation of the machine with said bar in inoperative 85 position.

16. A shoe machine having a member provided with work-positioning surfaces arranged to locate a plurality of articles in predetermined relation to each other, means for withdrawing said member to move said positioning surfaces to inoperative position, a latch arranged to hold said member in withdrawn position while the machine is further operated, and a member positioned adjacent 90 to the normal position of a part of the work piece at the conclusion of an operation thereon and arranged by impact of the work piece to release said latch thereby permitting the return of the work-positioning surfaces to 95 100 operative position.

17. A fastening-inserting machine having a reciprocable bar provided with a plurality of work-positioning surfaces, a spring tending to move said bar into position for the 110 engagement of said positioning surfaces with corresponding surfaces formed on the work, a dog reciprocable to withdraw said member from work-engaging position against the resistance of said spring, and a latch arranged 115 to hold said member in withdrawn position during further operation of the machine.

18. A fastening-inserting machine having a reciprocable bar provided with a plurality of work-positioning surfaces, a spring tending to move said bar into position for the engagement of said positioning surfaces with corresponding surfaces formed on the work, a dog reciprocable to withdraw said member from work-engaging position against the resistance of said spring, a latch arranged to hold said member in withdrawn position during further operation of the machine, and means positioned adjacent to the work arranged by impact of the work to trip said 120 125 130

latch and thereby to cause said bar and work-positioning surfaces to return to work-engaging position.

19. A shoe machine having a member provided with positioning pins arranged to enter corresponding holes formed in a plurality of articles positively to position said articles relatively to each other, said member being adjustably secured to the machine so that the relation of said positioning surfaces to the operating instrumentalities of the machine may be varied without varying the relation to each other of the articles positioned thereby.
- 15 20. A fastening-inserting machine having, in combination, fastening-inserting instrumentalities, and a work-positioning member provided with work-engaging surfaces arranged to co-operate with corresponding positioning surfaces formed on a plurality of articles to position said articles relatively to each other and to hold them against relative movement in all directions transversely thereof, said work-positioning member being arranged to permit variation of the relation of the positioning surfaces carried thereby to the fastening-inserting instrumentalities of the machine without permitting variation of the relation of said articles to each other.
- 20 21. A fastening-inserting machine having a nozzle, a driver arranged for reciprocation therethrough, and a work-positioning member provided with a plurality of positioning surfaces arranged to co-operate with corresponding positioning surfaces formed upon an insole and a last to locate the insole in predetermined relation to the last and to hold it positively against movement in all

directions transversely of the insole, said positioning member being pivoted to the machine to permit movement of the positioning surfaces relatively to the nozzle without varying the relation of the positioning surfaces to the insole and last so that the holes formed in the last by the insertion of successive fastenings may be distributed over a substantial area.

22. A fastening-inserting machine having a nozzle, a driver arranged for reciprocation therethrough, and a work-positioning member provided with one or more pins arranged to co-operate with corresponding holes formed in an insole and a last to locate the insole in predetermined relation to the last, said parts being arranged to permit movement of the pin or pins relatively to the nozzle without varying the relation of the pin or pins to the insole and last so that the holes formed in the last by the insertion of the successive fastenings may be distributed over a substantial area.

23. A shoe machine having a member provided with one or more pins arranged to enter corresponding holes formed in a plurality of articles to position said articles relatively to each other, said member being adjustably secured to the machine by a ball and socket joint so that the relation of said positioning surfaces to the operating instrumentalities of the machine may be varied without varying the relation to each other of the articles positioned thereby.

In testimony whereof I have signed my name to this specification.

ARTHUR F. PYM.
